UNITED STATES PATENT OFFICE.

GILES M. TURNER, OF MILWAUKEE, WISCONSIN.

DESIGN FOR A PEDESTAL.

Application filed August 11, 1922. Serial No. 3,352. Term of patent 14 years.

To all whom it may concern:

Be it known that I, GILES M. TURNER, a citizen of the United States, and residing in the city of Milwaukee, county of Milwaukee, and State of Wisconsin, have invented a new and original Design for Pedestals, of which the following is a specification, reference being had to the accompanying drawing, forming a part thereof.

The drawing shows a practical embodiment of my new design in pedestals for supporting various articles, one of common form being illustrated in dotted lines as an

example of one of the uses to which the pedestal may be put.

I claim:

The ornamental design for a pedestal, as shown.

In testimony whereof I have signed my name at Milwaukee, this 5th day of August, 1922.

GILES M. TURNER.
